SOUND MOTION PICTURE APPARATUS

Otto Wittel, Rochester, N. Y., assignor to Eastman Kodak Company, Rochester, N. Y., a corporation of New Jersey

Application May 19, 1939, Serial No. 274,656

4 Claims. (Cl. 271—23)

This invention relates to sound motion picture apparatus either projectors or cameras and particularly to the latter. It relates specifically to the film driving mechanisms in such apparatus.

It is an object of the invention to provide means for advancing the film with a uniform motion through the point at which the sound track is scanned. Obviously unless the film is constrained to move at a uniform and constant rate, there will be a distortion in the sound being recorded or reproduced.

It is a particular object of the invention to provide means for minimizing or eliminating entirely any non-uniformity of film motion due to a lateral motion, end-play or wobble of any of the gears in the train which drives the film.

It is well known that one of the smoothest types of gears comprises a disc gear driven by a worm. The term disc gear is here used to include both worm gear and spur gear. Such arrangements have the worm rotating at right angles to the disc gear and employ as a disc gear, a worm gear with oblique teeth set at an angle to match the pitch of the worm. However such systems are not quite perfect and any end-play, lateral motion or wobble of the disc gear (specifically a worm gear) causes these oblique teeth to shift so that the lateral motion is partially converted into tangential motion which, of course, involves a change in rotational speed of the disc gear. It is the specific purpose of the present invention to minimize or eliminate entirely any change in rotational speed due to such end-play or wobble of the disc gear.

According to the invention, the drum or sprocket which carries the film through the sound gate is driven, either directly or through a series of driving members by a disc gear which in turn is driven by a worm rotating at an acute angle (less than 90°) to the disc gear. Preferably the disc gear is a spur gear and has straight teeth (i. e. teeth parallel to the axis of rotation of this disc) and the worm is set so that its teeth (threads) mesh properly with the straight teeth. That is, the worm is set to rotate at an acute angle to the disc gear which angle is "equal" to the pitch of the worm. This defines "equal" as it is used in this specification and the accompanying claims.

With the disc gear and worm set in this preferable relation to each other, the rotation of the disc gear (specifically a spur gear in this case) is independent of any lateral movement of this gear (provided of course that it doesn't slip entirely out of mesh). This is due to the fact that any

such lateral motion such as due to end-play or wobble merely causes the disc teeth to move parallel to themselves along the worm teeth so that there is no tangential component of this lateral motion.

While the preferred embodiment thus described is necessary to eliminate completely the effects of end-play and wobble, there is a certain degree of improvement obtainable when the invention is 10 only partially applied, i. e. when the worm is set at an angle only approximating its pitch and the disc gear teeth are still slightly oblique. This less preferable embodiment may be necessary to allow a more compact or convenient arrangement 15 of the gear train.

It is desirable that the invention be employed in that part of the film driving mechanism which controls the steadiness of the film passing through the sound gate, but it is not necessary 20 that this be the sole force which advances the film. In those systems which employ a viscous drive whereby the sound head drum is maintained at a speed slightly less than the film speed (e. g. 1% less) and in which the film itself (driven 25 otherwise) assists in driving the sound drum, the invention is applied to the drum driving system and/or the film driving system. I prefer, in a sound camera for example, to couple the sound head drum or sprocket to a fly wheel, to drive the 30 drum and fly wheel by a viscous drive, to drive the viscous drive by a disc gear and to drive the disc gear by a worm mounted in accordance with the present invention. The worm may also drive 35 the other moving parts of the camera (preferably through a mechanical filter to prevent any feed back of the intermittent motions) and thus may be coupled to a film driving sprocket which pulls the film from the sound drum at a speed slightly 40 greater than that at which the viscous drive is rotating the drum. Thus the film assists in driving the drum and drives it at a speed slightly greater than that at which the viscous drive is moving.

Other objects and advantages of the present 45 invention will be apparent from the following specification when read in connection with the accompanying drawing in which:

Fig. 1 is a perspective view of one embodiment of the invention.

Fig. 2 is a front elevation of the arrangement shown in Fig. 1.

Fig. 3 illustrates another embodiment of the invention.

Fig. 4 is an enlarged fragmentary view of a gear coupling according to the invention.

In Figs. 1 and 2, a sound film (a sensitive film when the invention is used in a camera, a film with pictures and a sound track when used in a projector) is advanced with a uniform motion by a sprocket 11. The sound track on the film 10 is scanned by means of an optical system including a light source 12 and lenses 13. The "sound gate" is indicated by the point 18 and is known as a sound gate, whether or not there is any mechanical means for defining this particular point. The sprocket 11 is mounted on a shaft 14 and rotated thereby. The shaft 14 is in turn driven by a disc gear 15 having straight teeth parallel to the axis of rotation thereof, i. e. parallel to the shaft 14. According to the invention, this disc gear 15 (specifically a spur gear) is driven by a worm 16 mounted on a shaft 17 to rotate at an acute angle to the disc gear 15.

In the preferred embodiment illustrated, the angle at which this worm is set is equal to the pitch thereof. This provides that the threads of the worm 16 mesh properly with the teeth of the spur gear 15 and at the point of mesh, the threads of the worm 16 are also parallel to the shaft 14. Any end-play of the disc 15 on the shaft 14 or any motion of the gear 15 on the shaft 14 or any wobble of the gear 15 about an axis at right angles to the shaft 14 will merely cause the teeth of the disc gear 15 to mesh with the worm 16 at a slightly different point, but this change will introduce no additional rotation of the disc 15. Lamp 12 may be a glow lamp or ordinary sound valves may be used for recording.

In Figs. 1 and 2 the worm 16 is a triple thread gear.

The meshing of the gears is best illustrated in Fig. 4 where a double thread worm 16' meshes exactly with a disc gear 15' whose teeth are parallel to its axis (i. e. a spur gear).

In the arrangement shown in Fig. 3, the invention is combined with a system wherein the sound drum is driven by a viscous drive at a speed about 1% less than that at which this drum is driven by the film itself. In the arrangement shown, the sound gate is just to one side of the cylinder 20 (in this case a drum rather than a sprocket) which is mounted on a shaft 21 to rotate with a fly wheel 22. This drum 20 and fly wheel 22 are driven by a viscous drive comprising a housing 23 fitting closely around the fly wheel 22 and separated therefrom by a viscous medium such as oil in the chamber 28. The housing 23 is mounted on ball bearings 27 and is driven by a disc gear 24, all shown in cross section.

According to the invention this disc gear 24 is driven by a worm 26 mounted at an acute angle to the disc gear equal to the pitch of the worm. The worm 26 is carried by a shaft 25 which also drives a crown gear 31 through a beveled gear 30.

The crown gear 31 mounted on a shaft 32 drives a film sprocket 33 which advances the film 10 around the sound drum and pulls it from the sound drum at a speed slightly greater than that at which the viscous drive 23 rotates this drum 20. That is, the gear linkages between the worm 26 and the disc gear 24 provide slightly less peripheral speed than that provided by the beveled gear 30 and crown gear 31. Thus the film 10 assists to a slight degree in driving the sound drum 20. The drum 20 is mainly driven by the viscous drive 23, since the ease with which the fly wheel 22 may be rotated with respect to the housing 23 is a direct function of their relative speeds. That is, it is relatively easy for the film to drive the sound drum 20 at a speed slightly greater than that at which the housing 23 is rotating, but the viscous medium 28 prevents any great difference in speed between the drum 20 and the housing 23. Obviously, the shaft 21 must be free to rotate in the bearings 27.

Having thus described two preferred embodiments of my invention, I wish to point out that it is not limited to the specific structures but is of the scope of the appended claims.

What I claim and desire to secure by Letters Patent of the United States is:

1. A device for providing uniform film motion in sound motion picture apparatus comprising means in contact with the film for advancing it, means including a disc gear for driving the film advancing means and a worm in mesh with the disc gear for driving the latter, said worm rotating in a plane at an acute angle with the disc gear.

2. A device according to claim 1 in which the disc gear has teeth parallel to the axis of rotation of the gear and said acute angle is equal to the pitch of the worm.

3. In a sound motion picture camera, a device for advancing the film with a uniform motion past the sound gate, comprising a rotating cylinder adjacent to the sound gate for guiding the film through the sound gate, a fly wheel coupled to the cylinder to rotate therewith, viscous driving means for rotating the fly wheel and cylinder, a disc gear with teeth parallel to its axis of rotation for driving the viscous driving means, and a worm in mesh with the disc gear for driving the latter, said worm rotating at an angle to the disc gear equal to the pitch of said worm.

4. A device according to claim 3 in which there is a film sprocket also driven by the worm, said sprocket being positioned and geared to the worm to pull the film from the rotating cylinder at a rate slightly faster than that at which the viscous driving means rotates said cylinder, whereby the film itself assists in driving the cylinder.

OTTO WITTEL.
